BELT BUCKLE

Albert Bliss, Providence, R. I.

Application January 21, 1950, Serial No. 7,380

Term of patent 14 years

(Cl. D17—1)

To all whom it may concern:

Be it known that I, Albert Bliss, a citizen of the United States, residing at Providence, in the county of Providence and State of Rhode Island, have invented a new, original, and ornamental Design for a Belt Buckle, of which the following is a specification, reference being had to the accompanying drawing, forming part thereof.

Fig. 1 is a plan view of a belt buckle showing my new design; and

Fig. 2 is an edge view of the same.

I claim:

The ornamental design for a belt buckle, as shown.

ALBERT BLISS.
